APPLICATION FILED NOV. 25, 1904.

Fig. I

Fig. 2

Fig. 3

A line drawing of a human hand, palm facing forward. The fingers are numbered: the thumb is 4, the index finger is 2, the middle finger is 10, the ring finger is 14, and the pinky finger is 9. The palm is labeled with 18, and the center of the palm is labeled with 1. The number 5 is also present near the bottom of the hand.

UNITED STATES PATENT OFFICE.

DANIEL F. MORGAN, OF TOLEDO, OHIO.

GLOVE.

SPECIFICATION forming part of Letters Patent No. 784,115, dated March 7, 1905.

Application filed November 25, 1904. Serial No. 234,110.

To all whom it may concern:

Be it known that I, DANIEL F. MORGAN, a citizen of the United States, residing at Toledo, in the county of Lucas and State of Ohio, have 5 invented certain Improvements in Gloves, of which the following is a specification.

This invention relates to certain improvements in gloves, and more particularly in that class of gloves which are made from leather, fabric, or other suitable material cut and sewed in form; and the object of the invention is to provide a glove of this general character of a simple and improved nature in the manufacture of which a minimum number of pieces 15 are required, whereby economy is effected in the cutting and sewing of the glove and a novel and improved arrangement and location of seams is afforded, giving rise to increased strength and durability.

20 The invention consists in certain novel features of the construction, combination, and arrangement of the several parts of the improved glove whereby certain important advantages are attained and the glove is made 25 simpler, cheaper, and otherwise better adapted and more convenient for use, all as will be hereinafter fully set forth.

The novel features of the invention will be 30 carefully defined in the claims.

35 In the accompanying drawings, which serve to illustrate my invention, Figure 1 is an elevation showing the outline formation of the main or body portion of the improved glove. Fig. 2 is an elevation showing certain 40 features of the formation and location of the seam about the thumb portion of the improved glove as viewed from the palm with the thumb drawn down. Fig. 3 is a view of the back of the glove and also showing certain 45 features of formation and locations of seams. Fig. 4 is a view showing in outline the smaller or auxiliary part of the improved glove.

As shown in the views, the improved glove 50 is formed from two parts or pieces, a main or body portion 1 and a smaller auxiliary finger portion 2, the outlines of these parts or pieces being illustrated in Figs. 1 and 4, respectively.

The main or body portion 1 comprises in integral form all of the fourchettes or finger

members for the improved glove with the exception of the outer or back member for the third finger, which latter member is formed from the auxiliary portion 2, which in the course of manufacture is joined to the body 55 portion 1 in a well-known way, as will be hereinafter fully described.

The main or body portion 1 is designed to be centrally and transversely folded, as indicated by the dotted line at 3, so as to produce 60 therefrom palm and back portions or plies 5 and 6, the line of fold extending centrally along the side of the fourth finger 4, one member of which is thereby carried upon each of the said palm and back portions and 65 plies 5 and 6 of the glove.

Upon the palm portion or ply 6 of the improved glove are integrally produced the inner or palm members or fourchettes 8, 11, 13, and 20, respectively, of each of the successive 70 fingers and thumb of the glove, the members 8, 11, and 13 for the third, second, and first fingers being alongside of and projecting from the same edge of the body portion as the fourth-finger member 4. The member 20 for 75 the inner or palm side of the thumb, however, is produced at the opposite edge of the palm portion or ply 6, but in substantial alignment with the index-finger member or fourchette 13. The outer or back member 14 80 for the first or index finger of the glove is integrally connected with the inner or palm member 13 upon the ply or portion 6, being adapted to be folded over along the dotted line 15^a, (seen in Fig. 1,) so as to stand in position 85 upon the back or outer side of the glove.

Upon the back ply or portion 5 of the glove is produced the outer or back member or fourchette 10 for the second finger, and at the base of said member 10 is produced a space or opening 7, intervening between said member and the outer member or fourchette 4^a for the fourth finger, said opening or space 7 being transversely extended, so as to afford an edge portion for the attachment of the inserted 90 outer member for the third finger, which is produced from the auxiliary part or portion 2. (Shown in detail in Fig. 4 of the drawings.)

19 indicates the outer or back member or fourchette for the thumb of the glove, which 100

is also integrally produced upon the back ply or portion 5 alongside of the member 10, and 12 indicates a transversely-extended space or opening produced between these last-mentioned members 10 and 19 in a way similar to the space or opening 7, above referred to, said space or opening 12 being adapted for the insertion of the outer member or fourchette 14 for the first or index finger, which, as above 10 stated, is integral upon the palm ply or portion 6 and is adapted to be folded over upon the outer or back side of the glove, as shown in Fig. 3.

By this arrangement it will be evident that 15 upon the palm ply or portion 6 are produced the palm members or fourchettes for each of the several fingers and thumb of the glove, while upon the outer or back ply or portion 5 there are produced only the members 4^a, 10, 20 and 19 for the alternate finger and thumb portions of the glove—that is, of the fourth and second fingers and of the thumb—the intervening spaces 7 and 12 between these alternate finger and thumb members or fourchettes serving for the production thereon of lateral wings, as indicated at 10^a, affording the necessary fullness for closing the sides of the glove-fingers.

In joining the two parts or pieces 1 and 2 30 to produce the improved glove the several palm and back or outer members or fourchettes for the fourth, third, and second fingers are sewed in the ordinary way, the auxiliary part or portion 2 being stitched along 35 the opening 7 to produce a seam extended across the knuckle of the third finger, as shown at 9 in Fig. 3.

By the formation of the two members 13 and 14 for the first finger side by side and integrally connected upon the palm ply or portion 6 it is evident that the stitching of said finger along its outer side is avoided, and when the fourth, third, and second fingers have been closed in the ordinary way the outer 45 member 14 for the first finger will be folded over outwardly and stitched at its free edge to the opposite edge of the inner or palm member 13, so as to close the inner side of the first finger.

50 16 and 17 indicate edges produced upon the members 14 and 10 at the opening 12 and adapted to be stitched together, so as to effect a closure between the first and second fingers, and 15 indicates an inclined edge produced at 55 the lower part of the outer member 14 of the first finger, and which is adapted to be stitched along the edge of the opening 12 between the thumb and first-finger members on the back ply of the glove. By this arrangement an inclined or oblique seam is produced, extended 60 from the closure between the first and second fingers across the knuckle of the first finger to the side seam for the thumb portion, as shown at 18 in Figs. 2 and 3.

65 When the four finger portions of the glove

have been produced as above described, the outer member 19 for the thumb is lapped or folded over in substantial alinement with the first finger, as indicated in Fig. 2, after which the inner or palm member 20 of the thumb portion is sewed thereto around its edges, as indicated at 22, the adjacent edges of the back and palm plies 5 and 6 being then stitched along the wrist of the glove, as indicated at 23.

70 By the construction of the glove as above described it is evident that a material economy is effected in the manufacture, and increased strength and durability of the glove is attained, owing to the improved arrangement of the seam across the knuckle of the first finger to the side seam of the thumb, whereby that portion, 21, of the glove between the first finger and thumb upon the palm side is left free from seams. It will also be obvious from the above description that the improved glove is 85 capable of some modification without material departure from the principles and spirit of the invention, and for this reason I do not wish to be understood as limiting myself to the precise form and arrangement of the several parts herein set forth in carrying out my invention in practice.

Having thus described my invention, what I claim, and desire to secure by Letters Patent, is—

95 1. A glove comprising a palm ply or portion having integral fourchettes for the fingers and thumb, the fourchettes for the fingers being side by side and that for the first finger comprising palm and outer members integrally connected along one side and the thumb fourchette being at the edge of said palm portion opposite to said first-finger fourchette, and a back ply or portion having integrally-connected outer fourchettes for the thumb and second finger separated by a space in which is received the outer member carried by the first-finger fourchette of the palm ply of the glove, said outer member for the first-finger portion being stitched to the back ply by a 100 seam extended across the knuckle of the first finger to the thumb portion of the glove.

105 2. A glove comprising a palm ply or portion having integrally-connected palm members for the thumb and second finger and also provided with integrally-connected palm and outer members for the first finger and a back ply or portion having integrally-connected outer members for the thumb and second finger and provided with a space intervening 110 between said thumb and second-finger members and in which is received the outer member for the first finger, said outer member for the first finger being stitched to the back 115 ply or portion to produce a seam extended across the knuckle of the first finger to the thumb portion of the glove.

120 3. A glove comprising a body portion centrally folded to produce palm and back plies, the back ply having integrally-connected 125

outer members for alternate thumb and finger portions of the glove and having spaces between said integrally-connected members and the inner ply having integrally-connected palm members for each of the thumb and finger portions of the glove and having in addition an integrally-connected outer member for one finger portion of the glove, which

outer member is lapped in a space between the alternate thumb and finger portions at 10 the back ply and is sewed to said back ply.
